CLAIM

The ornamental design for a air touch wireless presentation apparatus, as shown and described.

DESCRIPTION

FIG. 1 is a perspective view of a air touch wireless presentation apparatus showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof; and,

FIG. 7 is a bottom view thereof.

The broken lines shown in FIG. 2 are included for the purpose of illustrating portions of the air touch wireless presentation apparatus and form no part of be claimed.
